UNITED STATES PATENT OFFICE.

JAMES H. FOX, OF BOWEN, MONTANA.

DERRICK.

SPECIFICATION forming part of Letters Patent No. 774,660, dated November 8, 1904.

Application filed March 21, 1904. Serial No. 199,072. (No model.)

To all whom it may concern:

Be it known that I, JAMES H. FOX, a citizen of the United States, residing at Bowen, in the county of Beaverhead, State of Montana, have 5 invented certain new and useful Improvements in Derricks; and I do hereby declare the following to be a full, clear, and exact description of the invention, such as will enable others skilled in the art to which it appertains to 10 make and use the same.

This invention relates to derricks, and more particularly to portable derricks such as are employed in stacking hay, the object of the invention being to provide a derrick which 15 may be made at a low price, will be durable and simple in construction, and which may be readily transported from place to place.

A further object of the invention is to provide a portable derrick embodying a base-frame and a mast adjustable thereon to lie at 20 various angles thereto.

In the drawings forming a portion of this specification, and in which like numerals of reference indicate similar parts in both views, 25 Figure 1 is a perspective view showing a derrick embodying the present invention. Fig. 2 is a section taken longitudinally through the roller and the adjacent portion of the base-frame.

Referring now to the drawings, the present derrick comprises a base-frame including sills 5 and 6, which are connected at their forward ends and which diverge rearwardly. At a point substantially midway between the ends 30 of the sills 5 and 6 are bearings 7 and 8, in which are mounted the trunnions 9 and 10 of a roller 11, to which the tower or mast of the derrick is connected by mortising into said roller the lower ends of the beams 12 and 13, 35 which form the sides of the mast. The beams 12 and 13 converge upwardly and are connected at their upper ends by the transverse piece or head 14, to which are connected braces

15 and 16 at the central part thereof, which diverge downwardly and are connected to the 45 beams 12 and 13. By reason of the mounting of the roller in bearings the masts of the derrick may be swung in a vertical plane to lie at various angles to the base-frame and with its head at various elevations, said mast being 50 held in its different adjusted positions by the guys 17 and 18, which are attached to the head 14 and to the rear ends of the sills 5 and 6, said mast being further held by a guy 19, which is attached to the forward end of the 55 base-frame and is forked at its upper end, the forked members 20 and 21 being connected to the head 14. The guys are attached to cleats on the base-frame, so that they may be manipulated to vary the angle between said frame 60 and the mast.

To give the proper rigidity to the base-frame, a transverse brace 22 is connected to the sills 5 and 6 in the rear of the roller 11.

Draft appliances 23 are attached to the forward end of the base-frame, so that the structure may be drawn from place to place.

What is claimed is—

A portable derrick comprising a base-frame comprising sills connected at their forward 70 ends and diverging rearwardly, a drum rotatably mounted transversely upon the sills, a mast including beams mortised at their lower ends into the drum and having a transverse head connecting their opposite ends and braces 75 between the head and said beams, guys attached to the head and to the rear ends of the sills and a guy attached to the forward end of the base-frame and having its upper end forked and connected to the head. 80

In testimony whereof I affix my signature in presence of two witnesses.

JAMES H. FOX.
